UNITED STATES PATENT OFFICE

HOMER A. MEAD, OF TURLOCK, CALIFORNIA, ASSIGNOR TO MASTERCHEM CORPORATION, OF TURLOCK, CALIFORNIA, A CORPORATION

WRENCH

Application filed May 16, 1929. Serial No. 363,426.

This invention relates to improvements in wrenches and particularly to one of that type having a fixed jaw and handle unit and a movable jaw pivoted in connection with the fixed jaw, and such as is shown in Patent No. 1,533,602 dated April 14th, 1925, and Patent No. 1,634,908, dated July 5th, 1927, and issued to myself and E. E. Lynch.

In both these previous devices a spring was employed to return the movable jaw to a closed position adjacent the fixed jaw. These springs are so arranged however that in the wrench of the first mentioned patent, if the movable jaw was turned to a full open position, the spring would disengage the lug provided on the jaw and the spring would then be so positioned as to prevent the ready return of said jaw to its closed position.

In the structure of the second mentioned patent the movable jaw could be fully opened and again closed but the spring when fully open would then be engaged at such a point in its length as to make it hard for the operator to move the jaw to such position.

The main object of the present invention therefore is to avoid the objectionable features of construction of the previous devices by arranging the spring in connection with a specially formed engaging surface provided therefor on the movable jaw in such a manner that regardless of the extent of opening of said jaw the spring would contact with said surface at substantially a constant point in the length of the spring at any position of the jaw.

The above object is carried out by means of such structure and relative arrangement of parts as will fully appear by a perusal of the following specification and claims.

In the drawings similar characters of reference indicate corresponding parts in the several views:

Fig. 1 is a side elevation of my improved wrench partly broken out showing the movable jaw closed.

Fig. 2 is a similar view showing the movable jaw in its fully open position.

Referring now more particularly to the characters of reference on the drawings, the

numeral 1 denotes the body or shank of the wrench having a handle 2 on one end of the same and a fixed jaw portion 3 on the other end; these elements being a one-piece rigid unit.

A longitudinal slot 4 is formed in said unit between the jaw and handle and terminates at one end adjacent said jaw. Projecting into this slot is the shank 5 of the relatively movable jaw 6 which is disposed outwardly of the shank 1 and the fixed jaw; a pivot pin 7 being passed through the shanks to mount the movable jaw in place for movement in a definite plane relative to the fixed jaw. The movable jaw is wider than its shank and is formed with side shoulders 8 at its junction with its shank, which shoulders are adapted when the jaw is swung to a fully open position to then aline with and abut against the edges of the shank 1, as in Fig. 2. The total movement of the movable jaw from its fully closed to its fully open position is approximately 90°. The face of the movable jaw which faces the shank 1 and the fixed jaw is so shaped, and the corresponding edges of the shank 1 on each side of the slot are also so formed or shaped relative to the jaw face as shown at 9, that when the movable jaw is in a fully open or spread position, said faces 9 will closely follow and engage four sides of a hexagonal nut N. The portion of the shank 1 which has said nut engaging faces formed therein may also therefore be considered as a portion of the fixed jaw. With a lesser extent of opening of the movable jaw the nut engaging faces thereof cooperate only with the outer curved surface of the jaw 3 beyond the slot to hold a relatively small nut as indicated in dotted lines in Fig. 1. Thus far the structure is substantially the same as shown in the previous devices already patented.

A flat spring 10 is fastened at one end to the shank 1 at the handle end of the slot 4 and on the same side or edge of said shank as that from which the movable jaw projects. This spring projects through the slot between the adjacent end of the slot and the back edge of the movable shank and at its free end en-

gages what I term a cam surface 11 formed on said back edge of the movable jaw shank. This cam surface is of such a length and is so positioned relative to the pivot 7 that with the turning of the movable jaw from a closed to a fully open position, the end of the spring only will remain engaged with said cam throughout the extent of movement of the jaw. Therefore while the spring of course is increasingly compressed with such movement the compressive pressure is applied to the spring only at its most flexible point at all times, and not at a point approaching its fixed end as was the case with the device shown in Patent No. 1,684,908 especially. Also the provision of the continuous spring engaging cam avoids the movable jaw then being prevented from returning of itself, or with the aid of the spring action, to its closed position as was the case with the structure shown in Patent No. 1,533,602.

To further insure the engagement of the spring with the cam only at all times and not with the edge of the jaw beyond the cam (which must bulge outwardly as shown at 12, to give the necessary strength to the jaw against breaking across where it is otherwise weakened by the nut engaging faces being cut into the same) the spring between its ends is convexly curved relative to such bulging surface so as to avoid contact with the same even when the movable jaw is fully opened and partly depends into the slot immediately ahead of the spring, as shown in Fig. 2.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A wrench including a handle shank having a fixed jaw on one end and a longitudinal slot adjacent the jaw, a shank projecting into the slot, a pivot pin through both shanks, a jaw on the pivoted shank outwardly of the slot, said pivoted shank and jaw being arranged for substantially 90° of arcuate movement relative to the handle shank, a flat spring member projecting through the slot beyond the pivoted shank and fixed at one end to the handle shank on the same side thereof as that from which the movable jaw projects, and a cam surface formed on the adjacent edge of the movable shank disposed relative to the shank pivot so as to engage the spring at substantially a constant point and adjacent the outer end of the latter through-

out the full arcuate extent of movement of the pivoted shank and jaw.

2. A wrench including a handle shank having a fixed jaw on one end and a longitudinal slot adjacent the jaw, a shank projecting into the slot, a pivot pin through both shanks, a jaw on the pivoted shank outwardly of the slot, said pivoted shank and jaw being arranged for substantially 90° of arcuate movement relative to the handle shank, a flat spring member projecting through the slot beyond the pivoted shank and fixed at one end to the handle shank on the same side thereof as that from which the movable jaw projects, and a cam surface formed on the adjacent edge of the movable shank for engagement with the spring and so disposed relative to the pivot pin and to the spring as to cause the spring to be increasingly compressed between the closed and open positions of the movable jaw while maintaining the spring engaged with the cam at a constant point in the length of the latter.

3. A structure as in claim 2, in which the spring, intermediate its ends, is shaped to avoid contact with the back edge of the movable shank beyond the cam irrespective of the extent of opening movement of the movable shank and jaw.

In testimony whereof I affix my signature. 95
